UNITED STATES PATENT OFFICE

GARRETT M. BRUGLER, OF BIG SPRINGS, OHIO

LOADING DEVICE

Application filed June 19, 1929, Serial No. 372,102. Renewed March 18, 1932.

The invention relates to loading devices, particularly manure loaders, and has for its object to provide a device of this character comprising a frame which may be supported on a conventional form of tractor and having a pivoted mast adjacent its forward end to which is pivoted an upwardly and outwardly extending boom to the end of which is pivoted a frame having a fork adapted to be forced 10 into material to be moved.

A further object is to pivotally mount the fork and to control the fork by a bar, which bar has one of its ends pivoted to a rearwardly extending arm of the fork, and its other 15 end slidably mounted in a latching device carried by the boom, and which latching device holds the bar in various adjusted positions whereby said fork, upon pivotal movement of the fork carrying frame in one direction, will 20 assume a position for entering material to be hoisted and when moved in the opposite direction the fork will assume a discharge position.

A further object is to slidably mount on 25 the fork, a fork cleaner having double link connections with the fork carrying frame and arms carried by the fork and having yieldable link connections with the double link connections, and forming means whereby upon 30 movement of the fork to discharge position, the cleaner will be forced towards the outer end of the fork and when moved in the opposite direction the cleaner will be moved to a position adjacent the inner end of the fork.

35 A further object is to provide yieldable links comprising a pivoted stationary member having slidably mounted thereon an elongated slotted member, into which lugs carried by arms of the fork extend, and spring 40 connections between the pivoted sections and slotted sections, whereby they are normally pulled towards each other, and are yieldably extended by engagement of the arm lugs with the outer ends thereof.

45 A further object is to slidably mount the latching bar in a sleeve carried by a rockable member carried on the pivoted boom, and to provide a pivoted yoke mounted on the sleeve and arching the rear end thereof, in the path 50 of the rear end of the latching bar for hold-

ing said latching bar against longitudinal movement. Also to provide the U-shaped member with an arm, to which a cable is connected for controlling the movement thereof, and spring means for normally maintaining 55 the U-shaped member in the path of the end of the latching bar.

A further object is to provide the fork with cables extending in opposite directions over pulleys carried by the fork and thence 60 over various pulleys to the rear end of the device for controlling the movement of the fork. Also to provide cable connections between the upper end of the mast and the fork frame at opposite sides of its pivotal point, 65 which cable connections extend downwardly through the mast and thence rearwardly to points adjacent the rear end of the loader and to rotatable drums driven by the rear tractor structure for controlling the pivoted fork 70 frame.

A further object is to provide drums driven 75 by the tractor differential and controlling cables extending forward and connected to yieldable arms carried by the mast turntable for rotating the mast and structure supported thereby to various positions. The yieldable connections absorb the shock incident to starting and stopping the rotation of the hoisting drums. 80

A further object is to provide cable means whereby the fork may be independently pivotally moved and cable means for controlling the latch of the latch bar for holding the latch bar and the fork in adjusted positions 85 after an adjustment of the fork for its proper loading and discharge angles.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention. 95

In the drawings:

Figure 1 is a side elevation of the forward end of the machine.

Figure 2 is a side elevation of the rear portion of the machine.

Figure 3 is an enlarged perspective view of the lower end of the mast, the turntable and the adjacent mechanism.

Figure 4 is a vertical transverse sectional view through the lower end of the mast taken on line 4—4 of Figure 1.

Figure 5 is a perspective view of the pivoted fork carrying frame and adjacent mechanism.

Figure 6 is a perspective view of one end of the fork shaft, showing a cable pulley carried thereby.

Figure 7 is an enlarged vertical longitudinal sectional view through the fork carrying frame and fork, showing the parts in shovelling position.

Figure 8 is an enlarged side elevation of the latch bar latching device.

Figure 9 is a top plan view of the latching device.

Figure 10 is a vertical longitudinal sectional view through the latching device.

Figure 11 is a top plan view of the horizontal frame and cable controlling mechanism, showing the turntable in top plan.

Figure 12 is an enlarged side elevation of one of the yieldable links.

Figure 13 is a horizontal sectional view through the inner end of one of the yieldable links.

Figure 14 is a top plan view of one of the yieldable links.

Figure 15 is a side elevation of the lower end of one of the control levers and its holding means.

Referring to the drawings, the numeral 1 designates the horizontal frame which is preferably U-shaped as shown in Figure 11, and is adapted to receive therein a tractor in a position where its rear axle housing 2 will be received within the U-shaped brackets 3 for attaching the frame to the tractor. The rear axle housing 2 is provided with the usual differential casing 4, which has therein a conventional differential which also drives the rearwardly extending shaft 5. Mounted on a platform 6 is a conventional form of hoisting mechanism having drums 10, 11, 12 and 13. The hoisting mechanism is provided with a bevelled gear 14, which is driven by the bevelled drive gear 15 carried by the rearwardly extending shaft 5. Therefore it will be seen that power for driving the hoisting device is obtained from the tractor drive mechanism, which may be of any construction or, if so desired, any kind of a hoisting device may be used, even a stationary type, and applicant does not limit himself in this particular, or to the specific construction of the hoisting device. The hoisting drums 10, 11, 12 and 13 are controlled by conventional clutch members 16, 17, 18 and 19 of the cam type shown in Figure 11, whereby any of the drums may be selectively locked to rotate with the shaft 20 of the hoisting device.

Extending upwardly from the forward end of the frame 1 is a mast 21 which is braced by the rearwardly diverging bars 22, and has its lower end provided with a turn-table 23, which is rotatably mounted on the frame 1. Extending downwardly from the turn-table 23 is a hollow extension 24 which is rotatably mounted in a spider 25 carried by the frame, therefore it will be seen that the mast can rotate for positioning the loading device hereinafter set forth in various positions. The mast 21 as well as the extension 24 are preferably hollow as shown so that the various cables may pass therethrough substantially on the axis of the mast, so that the parts controlled thereby will not be materially affected by any pulls on the cables incident to the rotation of the mast. Pivoted connected at 26 to the turntable are forwardly diverging arms 27, to the ends of which are connected rearwardly extending cables 28. The arms 27 are slidably mounted on the arcuate rod 29 as clearly shown in figure 3 and interposed between the arms 27 and lugs 30, carried by the turn-table 23, are coiled springs 31, which springs yield at the ends of the movement of the turntable for relieving the strain on the cables 28. The cables 28 extend rearwardly and terminate in pulleys 32, through which extend the cables 33, one of the ends of which cables is anchored at 34 to the frame 1, and the other ends extend rearwardly and around the drums 10 and 13, therefore it will be seen that the operator, while manipulating the levers 35 for controlling the clutches 16 and 19, may rotate the turn-table to any position desired.

Pivoted to the frame 1, adjacent the turntable 23 is a brake lever 36 which cooperates with the periphery of the turn-table 23 and is controlled by a rearwardly extending cable 37, which is connected to a conventional form of lever 38 adjacent the rear end of the frame, therefore it will be seen that the operator may immediately stop the rotation of the turn-table and still allow a slight movement of the cables 28 incident to the springs 31. The drum clutches 17 and 18 are controlled by levers 39 and 40 within easy reach of the operator on the tractor seat 41.

Pivoted at 42 to the turn-table 23 is an upwardly and forwardly extending boom 43, the upper end of which is in turn pivoted at 44 to the fork frame 45. Connected to the fork frame 45 below the pivotal point 44 are spaced blocks 46, through which a cable 47 extends, and which cable also extends over the pulley 48 carried by the pivoted mast head 49. One end of the cable 47 is anchored at 49a to the mast head while the lead end 50 of the cable extends rearwardly and over pulley 51 and into the mast 21. Connected to the upper end of the fork frame, above the pivotal point 44 is a conventional form of block 52, over which the cable 53 extends, and

which cable extends over the pulley 54 carried by the mast head and thence downwardly through the mast. One end of the cable 53 is anchored at 53a to the pivoted mast head 49, while the lead end 53b of the cable extends downwardly through the mast 21, and thence over the pulley 55 carried by the supporting spider of the turn-table 23, and thence outwardly and rearwardly over the pulley 56 and around the drum 12. Therefore it will be seen that by manipulating the drum 12, the upper end of the pivoted frame 45 may be moved.

The lead end 50 of the cable 47, which extends downwardly through the mast 21 extends over the pulley 57, similarly mounted to the pulley 55, and thence outwardly and rearwardly over the pulley 58 to the drum 11, therefore it will be seen that by manipulating the drums 11 and 14, the forked frame 45 may be moved to various angle positions in a vertical longitudinal plane for the shovelling and discharging operations. It will also be noted that the cables 53 and 47 have their lead ends 50 and 53b extending downwardly through the mast adjacent its axis, thereby obviating imparting pulls on the cables upon rotation of the turn table 23.

The fork frame 45 is substantially U-shaped and has pivotally mounted in bearings of its spaced arms 60, the pintles 61 of the fork shaft 62. The shaft 62 adjacent the pintles 61 is provided with pulleys 63, over which extend in opposite directions cables 64, and which cables extend rearwardly through pulleys 65 at the pivotal point of the frame 45, and thence downwardly and inwardly over pulleys 66 carried by the boom, and thence through pulleys 66a and 66b carried by the turn-table, and have their ends anchored at 67 to the pivoted arms 27 carried by the turn-table, therefore it will be seen that by manipulating the cables 28 with the brake 36 holding the turn table, the fork may be manipulated for adjusting the same to various angles during the shovelling operation.

Referring to Figure 7, the fork tines 69 is shown in position for piercing a stack of material, therefore in adjusting the device, the parts are placed in position as shown in said figure with the latch 68 engaging the end of the latch bar 69c as shown in Figure 10 for causing a pivotal movement of the fork upon rocking the frame 45 for the shovelling operation, and the latch bar is released and allowed to move longitudinally during a discharging operation as shown when the parts are in the position of Figure 5. The latching bar 69c is slidably mounted in a pivotally mounted bearing sleeve 70, reference being had to Figures 8 to 10, and which sleeve is carried by a pivoted bar 71 carried by the boom frame 43. Pivoted to opposite sides of the latch sleeve 70 is a U-shaped member 70a which arches the rear headed end

69a of a latch bar 69c, and holds the latch bar against longitudinal movement. The U-shaped member 70a is normally held in arched relation to the headed end 69a by means of a coiled spring 70b. The forward end of the U-shaped member 70a is provided with an arm 70c, to which is connected a downwardly extending cable 72. The cable 72 extends downwardly over the pulley 73, and thence over pulleys 74 and pulley 66b 75 which is a double pulley to the lever 27 for releasing the latch for discharge operation. It will be noted that when the latch bar 69c is released by the latch, the fork may be controlled at will through the manipulation of 80 the cables 64 and the device relatched by manipulating the cable 72 which controls the latch. After the fork swings downwardly for the discharge operation, frame 45, as well as the fork as a whole, through the control cables 64, are manipulated for returning the fork to shovelling position and for latching purposes.

To push the material from the fork when the fork reaches the discharge position as 90 shown in Figure 5, a vertically disposed plate 77 is provided, the ends of which are provided with downwardly and upwardly extending arms 78, which arch the under sides of the end tines 69 and connected to the arms 95 78 are rearwardly extending arms 79, the rear ends of which are pivoted at 80 to links 81, which links are in turn pivoted at 82 to the arms 60 of the frame 45. When the fork is moved to a discharge position, the links 81 100 approach positions in alignment with the arms 79, thereby forcing the plate 77 outwardly for pushing the material from the fork. When the fork approaches the loading position as shown in Figure 7, the arms 105 79 are folded towards registering positions in relation to the links 81 incident to the latch holding the latch bar 69c, which cause an upward movement of the out end of the fork. To absorb the shock and limit the 110 movement of the fork, the fork shaft is provided with upwardly extending arms 83, which have angular portions 84 slidably mounted in elongated slots 85 of pivoted arms 86, which arms are pivoted at 87 to the links 81 intermediate their ends, therefore it will be seen that the pivotal movement of the fork will be limited in its movement in either direction. It is obvious that the shock incident to the fork assuming the position shown in Figure 5 would be relatively great, and to overcome and take up this shock, the pivoted arms 86 are formed from stationary inner sections 88 having slidably mounted thereon the outer slotted sections 89, to opposite 115 sides of which are anchored plates 90 and spacing strips or U-shaped members 91, the transverse portions of which cooperate with the strips 92 carried by the members 89 for limiting the outward movement thereof.

120 125 130

Anchored to one of the plates 90 at 93 are coiled springs 94, the other ends of which are anchored at 95 to the pivoted sections 88 of the arms, therefore it will be seen that 5 when the members 84 carried by the fork arms 83 engage the ends of the slots 85, the springs 90 will be stretched, thereby absorbing the shock, and when the fork is returned to shovelling position, the shoulders 96 of 10 the arm members 88 will limit the inward movement thereof.

Although the device is described in connection with a fork, it is obvious that the same mechanism may be utilized for manipulating a shovel for shovelling or excavating purposes, therefore applicant does not limit himself in this particular.

From the above it will be seen that a loading device is provided which is simple in 20 construction, the parts reduced to a minimum, and one wherein the position of the fork and the movement of the fork is under the control of the operator at all times. It will also be seen that an automatic fork cleaner 25 is provided, which, when the fork is moved to loading position, will be automatically moved inwardly, and when moved to discharge position, will be automatically moved outwardly for discharging the material from 30 the fork, for instance into a vehicle.

The invention having been set forth what is claimed as new useful is:

1. A manure loading fork comprising a supporting boom, a fork frame pivoted to 35 said boom intermediate the ends of the fork frame, a fork shaft pivoted in the end of the fork frame, tines carried by the fork shaft, a rearwardly extending arm carried by the fork shaft, a pivoted bearing sleeve 40 carried by the boom, a latch bar pivoted to the rearwardly extending arm of the shaft and slidably mounted in the pivoted bearing sleeve, a latch carried by the sleeve and cooperating with the latch bar, and means 45 operating with the fork frame for pivotally moving the same.

2. The combination with a loading and shovelling device comprising a boom, a pivoted frame carried by said boom, a pivoted shovelling element carried by said pivoted frame, cable means cooperating with the pivoted frame and the shovelling element whereby they can be independently or simultaneously controlled, a latching bar carried by 55 the shovelling element, a sleeve carried by the boom and pivoted thereto, said latching bar being slidably mounted in the sleeve, a latch carried by said sleeve and cooperating with the latch bar for holding the same and 60 cable means for controlling said latch.

3. The combination with a pivoted loading and shovelling member, a pivoted frame, said member being pivoted to the pivoted frame, a boom, said pivoted frame being pivotally 65 connected to the pivoted boom, cable means

for controlling the pivoted shovelling element and the pivoted frame, of a latching means for the shovelling element, said means comprising an arm carried by the shovelling element, a latch bar pivoted to said arm, a sleeve rockably connected to the boom and in which the latch bar is slidably mounted and a spring actuated latch carried by said sleeve and cooperating with the latch bar for holding or releasing the same.

4. The combination with a pivoted loading and shovelling member, a pivoted frame, said member being pivoted to the pivoted frame, a boom on which said frame is mounted, cable means for controlling said pivoted frame and shovelling element, of latching means for further controlling the shovelling element, said latching means comprising an arm carried by the shovelling element, a latch bar connected to said arm, a sleeve pivotally connected to the boom and in which the latch bar is slidably mounted, a member pivoted to the sleeve and overlying the end thereof in the path of the latch bar for holding the same against longitudinal movement and means connected to said last named member for moving it out of the path of the latching bar when desired.

5. The combination with a loading and shovelling machine comprising hoisting drums, a frame, a mast pivotally mounted on said frame, a pivoted shovelling element, a pivoted boom adjacent the mast, a turn-table supporting said mast and boom, of means for controlling said shovelling element, said means comprising arms pivotally connected to the turn table, arcuate members on which said arms move transversely, springs on said arcuate members against which said arms yieldably engage, cable connections between said arms and the drums, cables connected to said arms and extending towards each other, pulleys carried by said turn-table and over which said cables extend, pulleys carried by the boom and over which 105 said cables extend, pulleys at the pivotal point of the frame, pulleys carried by the shovelling element, said cables extending over the pulleys at the pivotal point of the frame and over the pulleys of the shovelling elements 110 at opposite sides thereof.

In testimony whereof he hereunto affixes his signature.

GARRETT M. BRUGLER.
